UNITED STATES PATENT OFFICE.

JOHN SOKOLOWSKI, OF MILWAUKEE, WISCONSIN, ASSIGNOR OF FORTY-FIVE PER CENT TO PHILLIP DZIUBEK, FOUR PER CENT TO JOE EWASKOWITZ, FIFTEEN PER CENT TO WATER BABIARCZYK, AND FIVE PER CENT TO PETER TENEROWICZ, ALL OF MILWAUKEE, WISCONSIN.

ELECTRIC FURNACE.

Application filed December 29, 1922. Serial No. 609,689.

To all whom it may concern:

Be it known that I, JOHN SOKOLOWSKI, citizen of Poland, residing at Milwaukee, in the county of Milwaukee and State of Wisconsin, have invented certain new and useful Improvements in Electric Furnaces, of which the following is a specification.

This invention relates to stoves of the type which utilize electricity as the source of heat, 10 the invention having reference also to the provision of an electric stove, and of electric power generally, in places where a generator can be hydraulically operated, the invention having for an object the provision of a novel 15 type of electric stove combined with a water boiler.

For further comprehension of the invention, and of the objects and advantages thereof, reference will be had to the following description and accompanying drawings, and to the appended claims in which the various novel features of the invention are more particularly set forth.

Fig. 1 of the drawings is a diagrammatic 25 elevational view showing the means for generating the electric current.

Fig. 2 is a front view of the stove.

Fig. 3 is a side view thereof.

Fig. 4 is a diagram of the electrical connection.

Referring first to Figs. 2 and 3 of the drawings, my improved stove here comprises a lower portion 10 of rectangular shape and in which are several heaters, or 35 burners 11 of the usual type and located under an ordinary stove top 12. This lower member, or base, 10 is mounted on legs 13 carrying rollers 14 on their lower ends. These rollers may, if desired run on a suitable 40 track on the floor.

Extending upwardly from opposite sides of the base 10 are wall members 15 which have a box-like structure 16 on their upper ends in which is an oven closed by a hinged 45 door 17.

For heating water I provide a rectangular boiler 20 which is of substantially the size of the space enclosed by the side walls 15 between the stove top 12 and the upper 50 member 16. This boiler is fixed at its back to a standard 21 suitably secured to the floor so as to support the boiler. Extending upwardly through the boiler are tubes 22, of

which any desired number may be provided, and which are open at top and bottom, forming in effect flues extending vertically through the boiler. In these tubes are located electric heating coils 23 for heating the water in the boiler. As indicated at 24 and 24' respectively in Fig. 4 I may provide 60 the boiler 20 with a water gauge and steam gauge.

These coils 23 are arranged to be automatically switched into and out of the electric feed circuit as the stove is moved into 65 and out of the position shown in Fig. 3. To this end a suitably insulated contact member 25 is mounted on the bottom of the boiler and is adapted to engage a suitably insulated contact spring 26 carried by the stove 70 top 12. When the stove is moved forward, the space between the side walls 15 may form an oven, the front of the boiler 20 closing this space at the rear, while a hinged door 27 closes it at the front. A second 75 door 28 may close an opening in the front of the stove for access to the burners.

In Fig. 1 of the drawing I have illustrated a means for generating electric current, to supply the stove. In this case water 80 under pressure is derived from a suitably elevated collecting tank 30 and flows through a valve controlled pipe 31 to a water turbine 32 which drives an electric generator 33 through a suitable connection indicated at 34. The current from the generator is used to charge a storage battery 35.

In Fig. 4 I have indicated the electrical connections of my improved stove. The leads from the generator to the battery are 85 indicated at 40 and 41, the lead 40 having a hand switch 42 therein. From opposite sides of the battery main leads 43 and 44 extend. Lead 43 separates into two branches 45 and 46 respectively. Likewise the main lead 44 separates into two branches 47 and 48 respectively. The burner coils 11 are connected in parallel across the leads 46 and 47, suitable individual hand switches 49 being provided. The heating coils 23 are connected in parallel across the leads 45 and 48, the former having a hand switch 50 therein. The contact members 25 and 26 have connected thereto the leads 52 and 53 which bridge the switch 50. As will be apparent 100 105 the current can be supplied as desired to in-

dividual ones of the burner coils 11, or to the heating coils 23 as a unit, or to the two together.

While I have shown and described a preferred embodiment of my invention it is to be understood that I do not limit myself to the precise construction herein disclosed and that various changes and modifications might be made therein without departing from the spirit and scope of the invention as defined in the appended claims.

Having thus described my invention what I claim as new and desire to protect by Letters Patent of the United States is as follows:

1. In a stove, a base, electric burners therein, a boiler located above said base, and electric heating coils for said boiler, said boiler being formed with vertical flues in which said heating coils are located, said base being movable from under said boiler, and automatic circuit closing means for said coils adapted to cause the circuit to said coils

to be opened and closed respectively as the base is moved away from and under said boiler.

2. A stove comprising a movable base, side walls extending upward therefrom, a box-like structure supported on the upper ends of said side walls, a fixed boiler adapted to fit in the space between the said side walls, and heating coils in said boiler.

3. A stove comprising a movable base, side walls extending upward therefrom, a box-like structure supported on the upper ends of said side walls, a fixed boiler adapted to fit in the space between the said side walls, and heating coils in said boiler, and contact members controlling the circuit to said coils and adapted to automatically engage and disengage as the base is moved with respect to the boiler.

In testimony whereof I have affixed my signature.

JOHN SOKOLOWSKI.
